UNITED STATES PATENT OFFICE.

FORREST NAGLER, OF WAUWATOSA, WISCONSIN, ASSIGNEE TO ALLIS-CHALMERS MANUFACTURING COMPANY, OF MILWAUKEE, WISCONSIN, A CORPORATION OF DELAWARE.

HYDRAULIC MACHINE.

Application filed December 14, 1923. Serial No. 680,595.

This invention relates in general to improvements in the art of hydraulics, and relates more specifically to improvements in the construction and operation of hydraulic machines such as turbines and pumps.

An object of the invention is to provide an improved hydraulic machine which is simple in construction and efficient in operation. Another object of the invention is to provide an improved method of controlling the flow of liquid to or from a hydraulic energy converting machine such as a turbine or a pump. A further object of the invention is to provide structure whereby liquid may be more efficiently delivered to or discharged from a hydraulic rotor such as a turbine or a pump rotor, than has been possible with similar structures of the prior art. These and other objects and advantages of the present improvement will be apparent from the following description.

A clear conception of an embodiment of the present invention specifically applied to a hydraulic turbine, and of the method of operating machines constructed in accordance with the invention, may be had by referring to the drawing accompanying and forming a part of this specification, in which like reference characters designate the same or similar parts in the several views. While the embodiment illustrated specifically discloses a hydraulic turbine, it will be obvious that the principles involved are applicable to other hydraulic machines such as rotary pumps wherein it is frequently desirable to accommodate or to produce varying characteristics of the discharge flow.

Fig. 1 is a central vertical section through a hydraulic machine embodying one form of the improvement.

Fig. 2 is a transverse horizontal section through the unit disclosed in Fig. 1, the section being taken along the line II-II looking upward.

The hydraulic turbine installation illustrated in the drawing comprises in general an inwardly directed annular conduit communicating with a source 10 of water supply, a vane free transition space 11 adapted to receive water from the supply source 10 and to gradually change the direction of flow of the water from radial to axial, a flow decelerator or draft tube 9 adapted to receive the water which passes through the

transition space 11 after this water has had its flow changed from radial to axial, and an axial flow impeller or rotor 2 located between the transition space 11 and the draft tube 9. The cross sectional area of the inwardly directed or radial flow conduit connecting the supply source 10 with the transition space 11, is variable by means of a fluid pressure actuated plunger gate 5 which is movable along or parallel to the axis of the turbine. Within the radial flow conduit connecting the supply source 10 with the transition space 11, is located an annular series of stationary guide vanes 4 which penetrate the plunger gate 5 through openings 15, these vanes 4 being adapted to produce whirling motion of the water delivered to the transition space 11. The guide vanes 4 provide a support for the stationary frame 7 which in turn supports a bearing 8 located in close proximity to the rotor 2 and within the transition space 11. The inner portion of the plunger gate 5 which is located above the transition space 11 extends in close proximity to the bearing portion of the frame 7 and is downwardly curved to form a curved wall or annular lip 6 for directing the inwardly flowing water axially toward the turbine. The lower annular wall 12 of the transition space 11 is also curved for the purpose of changing the direction of flow of the liquid passing through the transition space 11, from radial to axial.

The rotor 2 has a series of radiating vanes 13 past which the whirling fluid advances in an axial direction. The rotor 2 is secured to one extremity of the main shaft 3 which is supported in the bearing 8, and the opposite extremity of which is connected to an energy translating device such as an electric generator, not shown. A gate actuating fluid admission pipe 16 surrounds and extends longitudinally of the main shaft 3 from a source of supply of air or other fluid under pressure, to within a short distance from the end of the bearing 8. The pipe 16 is of sufficient internal diameter to provide an annular fluid conducting space communicating with the annular chamber 14 formed within the plunger gate 5. The upper portion of the plunger gate 5 is provided with a removable cover 19 which embraces the pipe 16 and is slidably therealong. The joint between the cover 19 and the pipe 16

may be sealed by means of a stuffing box 17 in order to prevent escape of air from the chamber 14. The lower interior portion of the plunger gate 5 may be partially filled 5 with liquid from the supply source 10 as indicated, and a tubular extension 18 associated with the bearing 8 and extending above the level of the liquid within the chamber 14 may be employed to prevent undesirable 10 substances from entering and being deposited upon the wearing surfaces of the bearing 8.

During normal operation of the hydraulic turbine installation illustrated in the drawing, water is admitted from the supply source 10 inwardly past the stationary guide vanes 4 to the transition space 11. In passing the guide vanes 4, the water is caused to whirl about the axis of the unit. As the 15 whirling mass of water enters and advances through the vane free transition space 11, the plunger lip 6 and the surface 12 which bound the transition space 11, gradually change the direction of flow of the liquid 20 from radial to axial and deliver the water toward the vanes 13 of the rotor 2 as a whirling axially advancing mass. In passing through the rotor 2, the whirling mass 25 of water produces rotation of the rotor 2 and of the shaft 3 thereby converting some 30 of the energy of the water into torque in the shaft 3, and causing the shaft to rotate at a relatively high speed. The water delivered from the rotor 2 passes through the draft tube 9 and has its residual velocity 35 energy transformed into pressure energy.

If it is desired to vary the extent of opening of the plunger gate 5, air under pressure may be admitted or discharged through 40 the pipe 16, to or from the chamber 14, thereby causing the plunger gate 5 to move up or down as the case may be. The openings 45 in the lower wall of the plunger gate 5 permit free vertical movement of the gate 5 which is also guided upon the pipe 16 and upon the periphery of the frame 7. By releasing the pressure within the chamber 14, the plunger gate 5 may be entirely 50 closed, whereas admission of full pressure to the chamber 14 will produce full opening 55 of the gate as illustrated in Fig. 1. As the position of the plunger gate 5 is shifted, the lip 6 approaches or recedes from the bounding surface 12 of the transition space 11, the lower surface of the lip 6 and the surface 12 60 at all times cooperating to change the direction of flow of the water from radial to axial. It will be obvious that by thus expanding and contracting the area of the transition space 11, the quantity of water admitted to the rotor 2 as well as the direction of flow thereof, may be effectively controlled. The fluid pressure actuating means 65 for adjusting the plunger gate 5 may be

controlled in any suitable manner and the 65 packing effected by the stuffing box 17 and the liquid seal below the chamber 14 will effectively prevent escape of actuating fluid when the gate 5 has been set to the desired 70 position. The annular plunger gate 5 may be readily opened for inspection by removal of the top plate 19, whereupon the frame 7 and guide vanes 4 are freely upwardly removable from the gate 5.

It should be understood that it is not desired to limit the invention to the exact details of construction and of operation described herein, for various modifications within the scope of the claims may occur to persons skilled in the art. 75

It is claimed and desired to secure by Letters Patent:

1. In a hydraulic machine, a rotor of the axial flow type, a radial flow conduit at one end of said rotor and coaxial therewith, a 85 coaxial cylindrical gate extending across said conduit and having a flow guiding surface curving from radial to axial, and a series of vanes extending across said radial flow conduit within the periphery of said 90 gate but beyond the curved surface thereof.

2. In a hydraulic machine, a rotor of the axial flow type, a radial flow conduit at one end of said rotor and coaxial therewith, a coaxial cylindrical gate extending across 95 said conduit and formed to change the direction of flow of fluid passing therewith, and a series of guide vanes spanning said conduit within the periphery of said gate.

3. In a hydraulic machine, a rotor, means 100 forming a radial flow conduit at one end of said rotor and coaxial therewith, a cylindrical gate movable across said conduit and having a surface for changing the direction of flow from radial to axial, and an annular 105 series of guide vanes spanning said conduit within the periphery of said gate.

4. In a hydraulic machine, a rotor of the axial flow type, a radial flow conduit at one end of said rotor and coaxial therewith, a 110 coaxial cylindrical gate movable across said conduit and having a series of openings therethrough, and a series of guide vanes 115 spanning said conduit and extending through said openings.

5. In a hydraulic machine, a rotor of the axial flow type, a radial flow conduit at one end of said rotor and coaxial therewith, a coaxial cylindrical gate adjustable across 120 said conduit and having a series of through openings within its periphery, guide vanes spanning said conduit and extending through said openings, and fluid pressure actuated means for moving said gate.

In testimony whereof, the signature of the 125 inventor is affixed hereto.

FORREST NAGLER.
